UNITED STATES PATENT OFFICE.

SAMUEL F. LEAGER AND FRANK H. VLIET, OF SPOTSWOOD, NEW JERSEY.

SPARK PLUG.

Application filed September 2, 1921. Serial No. 497,821.

To all whom it may concern:

Be it known that we, SAMUEL F. LEAGER and FRANK H. VLIET, citizens of the United States, residing at Spotswood, in the county 5 of Middlesex, State of New Jersey, have invented a new and useful Spark Plug; and we do hereby declare the following to be a full, clear, and exact description of the invention, such as will enable others skilled in 10 the art to which it appertains to make and use the same.

The invention relates to spark plugs and has for its object to provide a device of this character, wherein the insulating core of the 15 spark plug is provided with a plurality of spaced rings adjacent its lower end, and adjacent the lower end of the spark plug shell, thereby forming in connection with a plate carried by the lower end of the electrode a 20 multiple of spark gaps extending entirely around the lower end of the core, thereby insuring sparking entirely around the core and at the same time forming spark gaps whereby the spark will be intensified.

With the above and other objects in view the invention resides in the combination and arrangement of parts as hereinafter set forth shown in the drawings, described and 25 claimed, it being understood that changes 30 in the precise embodiment of the invention may be made within the scope of what is claimed without departing from the spirit of the invention.

In the drawings:

Figure 1 is a side elevation of the spark 35 plug.

Figure 2 is a vertical sectional view 40 through the spark plug.

Figure 3 is a perspective view of one of the 45 rings carried by the lower end of the insulating core.

Referring to the drawings, the numeral 1 designates a metallic shell, the lower end 45 of which is provided with threads 2 adapted to be screwed into a cylinder head. Threads 2 are carried by a hollow cylindrical extension 3 which extends into the combustion chamber of the engine. Disposed in the shell 1 is an insulating core 4, which core 50 is held rigidly in place in the shell 1 by means of a lock nut 5 of the usual construction. The core 4 which is formed from in-

sulating material is provided with a downwardly extending cylindrical extension 6 axially disposed within the cylindrical extension 3 of the shell. Extension 6 extends to a point below the lower end of the cylindrical extension 3 and is provided with a plurality of spaced annular grooves 7 in which grooves are disposed split spaced 55 rings 8. Rings 8 are formed from conductor material and the upper ring is located adjacent the lower end of the cylindrical extension 3 thereby forming an annular spark gap, which the current jumps and from the upper 60 ring 7 said current passes to the lower ring 8 and thence to the metallic cap plate 9 carried by the electrode 10 which extends through the insulating member 4. As the current jumps the various gaps from the 65 lower end of the cylindrical portion 3 of the shell 1, from ring 8 to the adjacent ring and from the lower ring to the cap 9, it will be seen that the spark will be intensified, and that sparking will take place entirely around 70 the lower end of the cylindrical extension 6, thereby insuring uniform sparking, also an 75 intensified sparking, and at the same time uniformly igniting the charge within the cylinder.

From the above it will be seen that the spark plug is provided which is simple in construction and one wherein the spark will be intensified. It will also be seen that by providing split rings 8, that said rings may 80 be easily and quickly replaced when desired without damaging the plug thereby allowing the plug to be easily and quickly repaired.

The invention having been set forth what 85 is claimed as new and useful is:—

A spark plug comprising a shell, an insulator disposed in said shell and having its lower end spaced from the inner wall of the shell and its extreme lower end extending beyond the lower end of the shell, an annular inwardly extending integral flange carried by the lower end of the shell, split rings formed from conductor material surrounding the lower end of the insulator and disposed in annular grooves therein, the upper 90 ring being in the same horizontal plane as the annular inwardly extending flange, an electrode extending through the insulator, a conductor cap carried by the lower end of

the electrode and provided with an upwardly extending annular flange, said inwardly extending annular flange carried by the casing, split rings and upwardly extending flange, carried by the conductor cap being equidistant from each other.

In testimony whereof we have signed our

names to this specification in the presence of two subscribing witnesses.

SAMUEL F. LEAGER.
FRANK H. VLIET.
